C. S. WEBER

PIANO SOUNDING BOARD BRIDGE

Filed Sept. 18, 1922

Charles S. Weber

INVENTOR

UNITED STATES PATENT OFFICE.

CHARLES S. WEBER, OF HANFORD, CALIFORNIA.

PIANO SOUNDING-BOARD BRIDGE.

Application filed September 18, 1922. Serial No. 589,009.

This invention relates to piano bridges supported by the sounding board; its object is to obtain from the primary strings a clear tone; furthermore, to enrich this with sympathetic unisons derived from additional strings.

In annexed drawings Fig. I shows a crested bridge supported by the sounding board of a grand piano.

10 Fig. II shows the portion of strings under a section of bridge, encompassing seven notes.

Fig. III shows the portion above same section of bridge.

15 Fig. IV shows the preceding section in a front view.

Fig. V shows an improved stringing of the highest octave in an upright piano.

20 Figs. VI, VII, and VIII show a modification in the way of passing the strings from under the bridge.

Figs. IX and X are different views of a double crested sounding board bridge supported by the main sounding board.

25 Fig. XI shows different forms of crest.

As shown in the drawings there are on both sides of the sounding board bridge A holes for strings to pass from under to above it; the holes *m* are on the side farthest from the wrest pins; on the nearest side being the holes *n*. In stringing the piano, a string bent double may have one strand passed through a hole *m*, the other through *n* as shown in the notes F $\sharp$ and G, Fig. 2; or it may have both strands passed through holes on the same side, as in the notes G $\sharp$ and A, also in Fig. 8 showing a modification of the holes. All strands for each note, emerging on the side *m* farthest from the wrest pins *k*, cross the crest *c* in the direction of said pins, and form unisons in the main section *g* between *e* and the wrest bridge *i*. Strands emerging from holes *n* cross the crest directed to hitch pins *l*, and form unisons in the counter section between *c* and the hitch bridge *j*.

To prevent the portion of string under the bridge slipping whilst being tuned, I twist together two adjoining unisons, as close as practicable to their exit from under the bridge, as shown in the note A of Fig. IV, also in Fig. VII.

To provide for the contingency of a broken unison, I have an eye *t*, Fig. IV at the end

of said twist, for attaching a new unison 55 without the trouble of replacing the rest of the strings.

To secure two unisons at the point of their bearing on the crest, I use the spreader *s* Figs. IV and VIII; a slight elevation on 60 the slope of the bridge, having divergent sides to engage both unisons and hold them the proper distance apart. Improvement in tone is noted with the use of this device.

To prevent strings cutting the base of the 65 bridge, I use bottom shields *f*, Figs. I, II, IV, VI, and VIII. Where sounding board ribs *r* Fig. 2, make the surface uneven, I place along the holes *m* and *n* the required 70 number of short blocks *e*, equal in height with the ribs.

Means for equalizing the pull on opposite sides of the sounding board bridge are shown in a patent granted to me July 4th 1911 Ser. 557,538; other means subsequently discovered will be described in the following. Fig. V on its left shows five notes in the highest octave of an upright piano. In the counter section of said notes, besides the 75 multiple lengths, the primary note is also given, that would result, if the string, held at any of said marks, were sounded by a direct impulse. Thus C₇ held at the 6th mark will sound F₄, at the 7th it will sound a note between E₅^b and D₄ (not a step in 80 our scale); at the 8th mark, the note will be C₄, although, when influenced solely by sympathetic action of its main string the note will be C₇, no matter at which mark the counter string may be held as by a temporary bridge. Whilst the removal of this 85 device will leave equality of pull undisturbed; the two sections, with proportions of length altered, will have lost the ability to vibrate in unison. To avoid the complications that might result from a number of individual bridges made permanent; I use a principle so far new in stringing pianos and similar instruments. This allows expanding or contracting the lengths at which 90 sympathetic action results in two strings. To this effect I sustain the pull of a main string with a counter string of different thickness. The thinner string pulling against a thicker will have the greater tension, requiring a greater length for having 95 both to sound in unison.

Thus in the highest notes of a piano to

oppose the size 18, I may successively try sizes $12\frac{1}{2}$, 12, and 11; and select whichever should come nearest to placing the lowest mark in the centre of the hitch bridge j .
 5 Strings two sizes thinner than those in the main may be chosen in the counter section, this not being reached by the blow of an action hammer. To select the proper sizes and indicate the pitch to which the counter strings should be tuned, is left to the manufacturer. This task will be easiest in the highest octave of an upright piano where the relative length may exceed 16 to 1; in the truncated frame of a grand, towards the 15 middle notes of an upright, the proportion may not exceed three to one it may even fall to par. Heretofore said task has encountered new obstacles. I overcome these by varying besides the sizes the number of opposing units also; as shown in Fig. III, where the note B has two main strings opposed by four counter strings; in the note C the number of opponents is six. There being no less than 16 sizes of steel wire manufactured 20 thinner than the thinnest now used for main strings in pianos; so many combinations between numbers of units and their different sizes are at the disposal of the piano maker, that, no difficulty should be encountered for 25 having at least in the treble notes efficiency in sympathetic action combined with equal pull on both sides of the sounding board bridge.

To extend this improvement to the notes 30 of the bass I use the double crested auxiliary sounding board d' shown in Figs. IX and X.

Here the bass string g' instead of going from the crest c' directly to the hitch bridge j' is led under the auxiliary sounding board back to c'' to obtain sufficient length in its counter section between c'' and j' for a correct estimate of its tone and thereby of its tension, thus avoiding the alternatives of cutting short the main section, or deadening 45 its tone by short hitching.

Since the counter section in the bass notes is shorter than the main section, sympathetic action only results in overtones being heard in the shorter section, although indispensable 50 for establishing equal pull, they are not needed for acoustical effect in this invention, therefore the counter strings in this part are muted in any convenient way, to be open only during the act of tuning.

55 The four auxiliary notes to the right of Fig. V, 'C₇', 'B₆', 'B₅', 'A₆', may be contained within a strip two inches wide beyond the highest octave of a piano, even if their counter strings should be double the number, or 60 more, than those shown in the drawings. Not being reached by the action hammer the length of the main section is increased. The object is to further strengthen the often barely audible top notes of a piano. Reversing the order of succession places the

corresponding auxiliary at the side of the presumably weakest note of the usual scale, as shown in C₇ and 'C₇', Fig. V.

Sympathetic unisons derived from a short string may have no less amplitude than those originated in a long string; but the latter persist more, and may be heard for some time after the short string has ceased to vibrate. To gain in volume of tone an increase in the number of sympathetic units, as shown, has been found effective.

To control the vibrations in the counter strings I have invented the legato pedal; as shown in Fig. V, this consists of two boards u and u' , hinged on the frame of the piano 80 and operated by the performer in any convenient manner. The upper board holds a strip of felt to silence vibrations when not needed. The lower board u holds the harmonic divisors z . Instead of placing these 85 at the first or at the last mark of multiple lengths as shown in a patent granted to me on April 19, 1887, No. 361,384, Charles S. Weber, in the present improvement I place the divisor at the farthest mark found within a distance of 18 inches from the hitch bridge. Thus in the counter set of 90 C₇, the removal of the divisor from a distance of $2\frac{1}{4}$ inches to one of 16 inches, (the length of C₄) enables not only C₇ but 95 C₆, C₅ and C₄ also to obtain sympathetic unisons from said counter section altho by this limitation of lengths, six or eight central notes below A₃ may lose their share in 100 sympathetic unisons; forty upper notes, more in need of assistance, should profit by the change.

A slight pressure on the legato pedal lifts the upper board off the strings, and leaves the lower board with the attached divisors to regulate vibrations in said strings. Besides what already has been stated, the effect on the performer's play will be to smooth with sympathetic vibrations any break or 105 incoherency, often involuntary, between two consecutive notes; thereby creating an impression as if the notes were correctly held down. This position of the pedal therefore may be used to compensate for a deficiency in legato playing. Increased pressure on the pedal will lift the divisors off the counter section. With all lengths open sympathetic action is increased, but, not being controlled, some blur may occasionally be 110 noticed in the melody; not to a degree, however, as what may appear with the loud pedal we so often hear. In pianissimo parts, therefore, the second position of the legato pedal may be used as a substitute, or 115 in fortissimo passages, as a complementary to the loud pedal; one acting on the upper, the other on the lower notes.

In tuning the counter section, I sound the string with a pick, and stop turning the pin 120 just before the pitch is fully attained. In

the next step I only sound the main string, with short strokes of its key repeated about every second, whilst cautiously turning the same pin as before, and stopping when the 5 sympathetic response appears. Since a slight excess as well as a deficiency in pull causes this effect to vanish, the point to stop at is clearly enough indicated for executing this step without previous practice. As to 10 the first step; in a piano with strings once fully stretched it may need no repetition, unless in replacing a broken string.

Having described my invention, what I claim is:

In a piano, a bridge having two crests in combination with strings having main and counter sections for each note, one of said sections being located nearer the wrist pins than the others, the main sections of the strings for any one note resting on the crest 15 farthest from the wrist pins, and the counter sections of the strings for the same note resting on the crest nearest the wrist pins.

CHARLES S. WEBER.
